UNITED STATES PATENT OFFICE

ALEXANDER A. EMERY, OF CINCINNATI, OHIO

SHEAR SHARPENING DEVICE

Application filed November 13, 1931. Serial No. 574,809.

This invention relates to a shear sharpening device.

Among the objects of the invention are to provide means whereby an unskilled person may sharpen a pair of shear blades; to provide such means wherein a pair of shear blades may be successively held in identical position in order that a corresponding bevel may be formed on the blades by the passage thereover of a sharpening tool; to provide such a means which is adjustable to shear blades of varying lengths; and to provide the foregoing features in a shear sharpening device which is of simple and inexpensive construction.

Other objects and advantages of the invention will be apparent from the following description, considered in connection with the accompanying drawing, in which:

Figure 1 is a top plan of a shear sharpening device in accordance with this invention.

Figure 2 is an enlarged section taken substantially on the line 2-2 of Figure 1.

Figure 3 is an enlarged section taken substantially on the line 3-3 of Figure 1.

Figure 4 is an enlarged section taken substantially on the line 4-4 of Figure 1.

Figure 5 is an enlarged section taken substantially on the line 5-5 of Figure 1.

Referring to the drawing in detail, the numeral 1 indicates a base preferably in the form of a rectangular block supported on suitable buttons 2. At one end thereof, the block 1 is formed in its upper face with a recess 3 for receiving a metal plate 4 extending transversely of the block. One end of the plate 4 is formed with an enlargement 5 which is of materially greater thickness than the body portion of the plate, and an inner portion of which fits within a recess 6 in a side face of the block 1.

The enlargement 5 is formed with a notch 7 which extends vertically through the enlargement and opens through the outer side face thereof. The notch 7 is formed with opposing angular walls, one of which has a lower inclined portion 8, and the other of which has an upper inclined portion 9. The inclined portions 8 and 9 extend in parallel, inclined planes. The enlargement 5 is

formed with stops 10 and 11 at the outer extremities of the inclined wall portions 8 and 9 respectively.

Formed in the upper face of the plate 4, and opening into the notch 7 between the inclined planes of the wall portions 8 and 9 is an inwardly tapering groove 12 which opens at its inner end into an elongated slot 13 extending lengthwise of the plate 4. Slidably mounted on the plate 4 is a tapered adjustable member 14 formed with a groove 15 disposed in alignment with the groove 12. Depending from the member 14, and extending through the slot 13, is a lug 16 which is apertured to receive therethrough a bolt 17. The bolt 17 extends through a recess 18 in the block 1 beneath the plate 4, and is provided with a nut 19 and washer 20 for engagement with the block 1 and plate 4 to maintain the member 14 in adjusted position with respect to the length of the groove 12.

In the use of the device, one shear blade, such as 21, is extended through the notch 7 in engagement with the inclined wall portions 8 and 9. The other shear blade, such as 22, is disposed within the grooves 12 and 15, the member 14 being adjusted in accordance with the length of the blade 22. A sharpening tool, such as a file indicated at 23 is then drawn transversely against the blade 22 in order to form the cutting edge of the latter with a bevel 24 which is parallel to the upper face of the block 1. Preferably the file 23 will be provided with a handle member 25 which is of appropriate thickness to maintain the file in parallel relation to the block 1 when the handle member 25 is seated on the block. After the blade 22 has been sharpened, the positions of the blades 21 and 22 are reversed in order that the blade 21 may be sharpened in the same manner. The blade which is being sharpened is always maintained at the same inclination when disposed within the grooves 12 and 15, owing to the contact of the other blade with the inclined wall portions 8 and 9 of the notch 7, consequently the bevel formed on the blade by the reciprocation of the tool 23 in a line parallel to the upper

face of the block 1 necessarily will be of the same pitch.

While the embodiment of the invention herein illustrated and described is to be considered as a preferred example of the same, it is to be understood that changes in the details of construction may be made, so long as such changes fall within the scope of the appended claims.

I claim:

- 10 1. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate.
- 15 2. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate, said notch having opposite wall portions extending in inclined, parallel planes.
- 20 3. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate, said notch having opposite wall portions extending in inclined, parallel planes.
- 25 4. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate, said notch having opposite wall portions extending in inclined, parallel planes.
- 30 5. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate, said notch having opposite wall portions extending in inclined, parallel planes.
- 35 6. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate, said notch having opposite wall portions extending in inclined, parallel planes.
- 40 7. In a shear sharpening device, a supporting block formed adjacent one end with a recess, a plate disposed within said recess and extending transversely of the block, an enlargement on one end of the plate formed with a blade receiving notch, said plate having its upper face formed with an inwardly tapering groove with its outer end in communication with said notch, said plate further being formed with a lengthwise extending slot in communication with the inner end of said groove, a slidable member mounted on the plate and having a lug extending through said slot, a bolt extending through said lug, and tightening means on the bolt for engagement with the block and plate, said notch having opposite wall portions extending in inclined, parallel planes.
- 45 8. In testimony whereof, I affix my signature hereto,

ALEXANDER A. EMERY.
